UNITED STATES PATENT OFFICE.

JOHN R. SCOHY, OF OKMULGEE, OKLAHOMA.

GLASS CUTTER.

1,411,524.

Specification of Letters Patent. Patented Apr. 4, 1922.

Application filed December 11, 1920. Serial No. 429,843.

To all whom it may concern:

Be it known that I, JOHN R. SCOHY, a citizen of the United States, and a resident of Okmulgee, in the county of Okmulgee and 5 State of Oklahoma, have made an Invention Appertaining to Glass Cutters; and I do hereby declare the following to be a full, clear, and exact description of the invention, such as will enable others skilled in the 10 art to which it appertains to make and use the same, reference being had to the accompanying drawings, and to the characters of reference marked thereon, which form a part of this specification.

15 My invention has for its object to provide a means for readily cutting glass. It particularly has for its object to provide a glass cylinder cutter which may be readily manipulated to sever the glass cylinder into 20 parts. In constructions containing my invention I provide a means for holding a glass cutter point such as a diamond or wheel in a definite position relative to the surface of the cylinder while the point is being drawn around the cylinder.

25 The invention may be contained in structures of different forms and to illustrate a practical application of the invention I have selected one of the structures containing the 30 invention and shall describe it hereinafter. The structure selected is illustrated in the accompanying drawings.

Figure 1 of the drawings is a top view of the glass cutter and Fig. 2 is a sectional view taken on the line 2—2 indicated in Fig. 1.

35 1 in the figures is a frame having the sides 2 separated and maintained in a parallel relation by means of the block 3 that extends between the upper edges of the sides 2, and by the bolts 4 that extend through the sides 2 and the block 3. A bolt 20 may be 40 also provided for securing the sides 2 in their position with reference to each other. 45 The lower edges 5 of the sides 2 are curved so as to conform substantially to the shape of the cylinder 6 to be cut.

The block 3 is provided with a spring 7 that extends beyond the block 3 and is 50 cured at one end to the block 3 by means of the screw 8. The position of the free end of the spring 7 is adjusted by means of the thumb bolt 9 which is threaded into the block 3.

A bar 10 extends between the sides 2 and 55 is adjustably secured from rotation by means of the thumb nuts 11 located on studs that are formed integral with the bar 10. The studs 12 extend through the sides 2 and the sides are clamped by the thumb nuts 11. 60 A sheath or quill 13 is secured in the central part of the bar 10. The sheath is provided with fingers 14 formed by slots extending lengthwise of the sheath or quill, and these are bent slightly inward so as to frictionally 65 engage the handle 15 on which is located the glass cutting wheel 16. The length of the handle 15 is such as to be engaged with the free end of the spring 7, and by reason of the adjustability of the spring 7 by means 70 of the threaded bolt 9 the handle 15 may be pressed towards the glass cylinder with any desired pressure. Also since the bar 10 is adjustable the angular position of the handle 15, and consequently the direction of pressure of the cutting wheels 16 against the glass cylinder, may be varied. The handle 15 may be provided with a collar 18 that may be adjustably secured by means of the pin 19 to the handle to limit the movement of 75 the handle that may be induced by the spring 7 when the cutter is raised from the cylinder. If desired, a flexible strip 17 may be secured around the glass cylinder as a guide for the glass cutter. One of the edges 80 of the sides having substantially the same curvature as the glass cylinder 6, may be placed against a flexible bar 17 and the frame 1 together with the glass cutting point may be drawn around the cylinder, 85 keeping the side against the flexible strip 17. 90

By this means the pressure exerted on the point 16 will be maintained constant and the direction of the pressure of the point 16 against the glass surface will also be maintained constant.

I claim:

1. In a glass cutter for severing glass cylinders a frame, the edges of the frame having a curvature substantially the same as 100 that of the glass cylinder to be cut, a glass cutter pivotally mounted on said frame and having cutting point, means for producing a substantially constant pressure of the glass cutting point, and means for maintaining a constant direction of pressure relative to the portion of the surface of the glass cylinder against which the point is pressed. 105

2. In a glass cutter for severing glass cylinders a frame, the edges of the frame having a curvature substantially the same as that of the glass cylinder to be cut, a glass cutting point, a handle connected to the point, a spring supported on the frame for pressing against the end of the handle, a sheath for receiving and frictionally en-

gaging the end of the point, an adjustable bar for holding the sheath in a definite position relative to the surface of the glass beneath the point. 10

In testimony whereof, I have hereunto signed my name to this specification.

JOHN R. SCOHY.
